UNITED STATES PATENT OFFICE.

GEORGE W. ATKINSON, OF SPRINGFIELD, MASSACHUSETTS.

JACK RECEPTACLE-TESTING DEVICE.

Application filed March 10, 1925. Serial No. 14,421.

This invention relates to improvements in a type of jack receptacle testing device. It is of particular utility where permanent means is to be provided in an electrical circuit for making a quick, easy, and safe method of ascertaining the load condition on a current consuming apparatus. The said device is formed with a threaded neck portion so that this part will fit into a hole, 10 as for instance, the knockout hole, in the wall of a sheet iron cabinet, box, or casing which encloses some part of an electrical circuit. It permits that no extra space need be provided for its installation in existing 15 or standard arrangements of an electrical system. On the threaded neck portion of the device or receptacle which protrudes through a wall of said cabinet, box, or casing a lock nut is provided to permanently 20 hold the receptacle in place. In case it is desirable to install the receptacle entirely within a cabinet or other enclosure, I have provided a special form of bracket as will be described and which is formed with an 25 opening to receive the threaded neck of the receptacle. The opening in this bracket receives the threaded neck portion of the receptacle after which the lock nut may be threaded onto the neck portion to hold it 30 as above stated. In order to secure the receptacle permanently in the wall or side of a cabinet or enclosure, the bracket is then bolted to the side of same as indicated.

The electrical connection to this receptacle is made by connecting any series wire to the usual two lugs, as shown. In its application the improvement is not intended to be limited to any particular arrangement of being connected in the circuit, but is generally connected between the load and some protective device such as fuses or circuit breakers.

This form of receptacle is compact and readily lends itself in that it may be readily 45 installed in an existing installation of electrical circuits, which may be partly enclosed in a cabinet, box or other casing. Generally speaking it occupies a comparatively small volume of space and is well 50 adapted for installation in the sides or corners of cabinets, boxes, or enclosures where it will not occupy spaces that are useful for other purposes, and at the same time it will possess the required spacing distances 55 for electrical insulations.

The improvement broadly considered

comprises a main body which is composed of insulating material. It is formed with a small rectangular aperture in the top end of the said neck portion of the receptacle 60 which forms a space for the insertion of the test plug. An insulating cover is provided over this aperture and arranged to be readily moved from the closed to the open position or vice versa. The current carrying 65 members of the receptacle are composed of a metal having a spring action as well as being a good electrical conductor. In order to insure an adequate electrical contact, between the adjacent leaves of the current carrying members of the receptacle, I have installed the steel springs. These springs together with the current carrying members are shaped and installed in such a manner 70 that they will permit the insertion of the 75 testing plug and still retain the necessary pressure between electrical contacts at all positions of the test plug. The current carrying members on the receptacle are laminated in order to insure better electrical 80 contacts and to permit of greater ease in operation when making tests.

A portable testing plug is provided, as indicated, having a main body which is constructed of insulating material. It is divided longitudinally in practically two equal sections which are held together with bolts. The set of bolts on each end serve the additional function of securing the handle supports to the main body. By having the 90 main body divided into two sections, the electrical connections to lugs and test plugs are made readily accessible. The two main halves of contactors of the test plug are separated electrically by means of the thin layer 95 of insulating material. On the lugs attached to each test plug contactor, there are attached two leads or electrical conductors which may be of suitable length to accommodate connection to an ammeter or wattmeter used in making tests. To understand now quite exactly how a device embodying 100 my invention functions and operates in actual service after it has been arranged and connected practically as shown in the figures, or 105 in some other way within the purview of the invention reference may now be had to the drawings. Here it will be seen that the current carrying part of the receptacle is connected in series with the circuit and is accessible 110 for insertion of the test plug contactors. When the contactors of the plug

are first started between the current carrying parts of the receptacle, a portion of the electrical current going through the receptacle conductors is diverted to the circuit being 5 made through the test plug with its connected measuring instrument. The amount of current going through this instrument gradually increases as the plug contactor is further inserted, but it reaches a maximum 10 amount when the two main sections of receptacle current carrying parts are electrically separated by the test plug contactors pushing them apart. After the proper readings of the load conditions are obtained the 15 test plug is pulled out of the receptacle and the current flowing through the test instrument is gradually decreased in amount as the plug is removed. The construction of this device is such that it is impossible with- 20 in all practical means of operation, to cause an open circuit, short circuit, or ground, while making a test connection, or disconnecting the same. The current is gradually built up and decreased through the testing 25 instrument during the cycle of testing. There is no arcing at any place in the circuit as the current is gradually transferred to and from the circuit of the testing instrument. This condition obtains within all 30 practical time taken for inserting or removing the test plug.

I have thus far referred to arrangements similar to the structure shown, which may be installed in existing cabinets, boxes or 35 other enclosed devices for electrical circuits, but I do not intend to imply that my invention is not equally available for installation in cabinets, or boxes especially made for enclosing same and connected in the electrical 40 circuit system. However, due to its compactness and simplicity of installation it is particularly well adapted for being installed in existing cabinets, boxes, or other enclosing devices now in place, or in such 45 standard cabinets, boxes or other enclosing devices which may be installed at a future time.

Referring to the drawings:

Fig. 1 is a plan view of the receptacle, 50 showing in dotted lines the terminals and the opening which receives the blades of the contactor.

Fig. 2 is a top plan view of the contactor assembly.

Fig. 3 is a vertical sectional view on the line 3—3 of Fig. 1 showing the flexible contact leaves, the threaded neck portion, and the lugs.

Fig. 4 is a side view of Fig. 2 showing 60 the handle part and the contactor blades.

Fig. 5 is a detail view of the device installed entirely within one corner of a cabinet or casing.

Fig. 6 is an enlarged side view partially 65 in section on the line 6—6 of Fig. 5 show-

ing a modification of installation with an apertured bracket.

Fig. 7 is a view showing the receptacle installed ready to be connected to a measuring instrument, and 70

Fig. 8 is a perspective view showing the receptacle attached to a bracket, and, with the cover plate in an open position.

Referring to the drawings in detail:

1 designates, as a whole, the body part 75 of the receptacle which is formed with a hollow recessed interior part 2. Located within this recessed part are the U-shaped contact spring leaves 3 and 4; one end of which is attached to the opposite interior walls of the recessed part by means of the bolts and nuts 5 and 6; the other or inner ends of these leaves extend downward in contacting relation to each other toward the lower end of the recessed part 2, as shown. Disposed between the outermost leaves 3 and 4 and the inner wall of the recessed part are filler or spacing plates 7. Each set of contact leaves comprises a plurality of members as shown, and are of varying lengths. 8 and 9 designate two curved springs which are interposed between the lower ends of the innermost ones of the leaves 3 and 4 and the inner ends of the bolts 5, to which bolts they are secured by the nuts 6. These curved springs are for the purpose of normally retaining the depending inner ends of the contact springs 3 and 4 together and exerting the necessary pressure between leaves for good electrical contact. The upper end of the insulating member 1 is formed with a threaded neck portion 10, and this upper end or wall part is provided with a rectangular shaped opening 11 which is arranged in axial alignment with the meeting surfaces of the contacting leaves 3 and 4. 12 designates a cover plate of insulating material which is pivotally attached to the upper surface or end of the part 1 by means of the pin 13. 100

The lower outer ends 14 and 15 of the leaves 3 and 4 are bent at right angles, as shown, and extend outward in opposite directions below the lower ends of the member 1. These ends afford attaching means for the usual cable connections 16 and 17, as with the bolt 18. 115

The receptacle 1 is installed or attached to a wall of metallic casing as 19 by inserting the threaded neck portion 10 in a knockout opening. It is secured in place by means of the nut 20, see Figs. 7 and 8. 120

As a modification of installing the receptacle 1 in a casing or housing I make use of the bracket 21 having the arm part 22 which is formed with an opening 23, see Fig. 6, to receive the threaded neck part 10 of the receptacle 1. The lock nut 20 is threaded onto this neck part which retains the receptacle in place on the bracket. The 125 130

bracket is secured to the wall of the casing by means of the bolts 24 which pass through the openings 25. In Fig. 5 the receptacle is normally enclosed in the metallic casing; the door of which is usually closed and locked.

In Fig. 7 the receptacle 1 is enclosed in the casing 19 but its outer threaded end 10 projects through a knockout opening in a wall of the same and is secured in place by 10 the lock nut 20 as before described. This figure and Fig. 5 show the wires 16 and 17 connected to the terminals 14 and 15 of the receptacle. Fig. 7 shows a switch operating handle 26. 27 are the fuses which 15 are removably inserted in the knife blades 28.

Referring now to the contactor construction shown in Figs. 2 and 4, 29 and 30 are the three oppositely located blades of 20 unequal length, as shown. The innermost blades are separated by the strip of insulation 31. The blades 29 and 30 extend upward and are bent in opposite directions to form the branches 32 and 33. 34 and 35 25 are two clamping members between which the branches are clamped by means of the bolts 36 and 37. The bolts 37^a serving the purpose of electrically connecting the branches to the lugs 38 and 39. The bolts 36 serve also to attach the handle supporting bars 39' to the upper ends of which the handle 40 is attached. 41 is an electrical measuring instrument as a wattmeter, or 30 ammeter which is connected by the wires 35 42 to the lugs 38 and 39.

It will be observed that when the contactor blades 29 and 30 are inserted between the outermost leaves 3 and 4 that the current which normally flows through the leaves 40 3 and 4 is divided, part flowing through

the leaves and part through the contactor blades 29 and 30 as these blades are inserted. The circuit is not, therefore, opened at any time when the blades 29 and 30 are removed. The reverse operation takes place 45 when the contactor blades are withdrawn. In other words the load may be measured at any time without breaking the circuit, when the contactor blades are inserted the 50 springs 8 and 9 yield to permit the insertion, and, when the blades are removed they will automatically return the leaves 3 and 4 together again as the blades are withdrawn. The current always flows in series 55 through the leaves 3 and 4 and, in series through the contactor blades 29 and 30 when inserted.

What I claim is:

An electrical testing device comprising 60 an insulating member formed with a recessed portion, the insulating member having a threaded extension portion for securing the member to a fixed support, which is formed with an opening to receive the thread extension, a nut engaging the threaded extension of the insulating member for securing the said member to the support, electrical contact members located within the recessed portion, means for forcing said members together in contact with each other, 65 the insulating member having an opening through the threaded extension and designed for inserting a single contactor member between the normally closed electrical contact members, the construction and arrangement 70 being such that the contactor may be inserted and removed without breaking the circuit.

GEORGE W. ATKINSON.
